Ernest W. Bradford

UNITED STATES PATENT OFFICE.

ERNEST W. BRADFORD, OF INDIANAPOLIS, INDIANA.

MAIL-POUCH DELIVERER.

SPECIFICATION forming part of Letters Patent No. 496,551, dated May 2, 1893.

Application filed October 3, 1892. Serial No. 447,619. (No model.)

To all whom it may concern:

Be it known that I, ERNEST W. BRADFORD, a citizen of the United States, residing at Indianapolis, in the county of Marion and State 5 of Indiana, have invented certain new and useful Improvements in Mail-Pouch Deliverers; and I do hereby declare the following to be a full, clear, and exact description of the invention, such as will enable others skilled in 10 the art to which it appertains to make and use the same.

My invention consists in various improvements in the construction and arrangement of an apparatus for delivering mail pouches 15 to or from postal cars while in motion, whereby an electric current is utilized to set off, or trip, the operating mechanism, all as will be hereinafter more fully described and claimed.

Referring to the accompanying drawings, 20 which are made a part hereof and on which similar letters of reference indicate similar parts:

Figure 1 is a cross section through a postal car provided with my improved apparatus, and 25 also through the apparatus set along-side the track, and Fig. 2, a horizontal section showing the principal part of the mechanism in top plan.

In said drawings, the portions marked A 30 represents the car, B a box or receptacle located beneath the floor of the car, C a flexible apron, D an electric battery, E a magnet, F a post along-side the track, G a receptacle on said post, H a flexible apron in said receptacle, 35 and I a magnet on the post.

The car, A, is of the usual construction, and the receptacle, B, is of a suitable size to receive a mail pouch. It is located beneath the floor of the car close to one edge thereof, communication being had thereto from the car 40 through a trap door in its floor, or may be located in any other suitable place desired.

The flexible apron, C, is of substantially the same width as the box or receptacle, B, and 45 at one edge is fastened to the lower front edge thereof, its rear edge being connected by a cord, c, to an operating spring, C', said cord being passed over a sheave, c', at the upper rear corner of the receptacle and under an 50 other sheave, c'', at its front corner, then up along-side the wall of the car and connected to said spring. An enlargement or knot, c''

is provided on said cord, and a pivoted metal catch, c'', is arranged adjacent thereto provided with a notch on one side with which 55 the cord may engage by means of the enlargement, c'', in a position to hold the spring, C', distended and permit the apron to lie substantially flat in the bottom of the receptacle.

The battery, D, consists of a suitable number 60 of cells conveniently located in any suitable case in the car.

The magnet, E, is of a usual construction and is located adjacent to the side of the catch, c'', opposite that containing the notch. 65 It is connected by a wire, e, to the battery and another wire, e', runs therefrom to a brush, E', which is secured to a convenient portion of the truck frame of the car in position to contact with another brush, I', secured along- 70 side the track, but insulated therefrom.

The post, F, is any suitable post for supporting the mechanism along-side the track.

The box or receptacle, G, is mounted rigidly on the post, being similar in construction 75 to the box, B, on the car. The flexible apron, H, therein is also similar to the apron, C, and is operated by a spring, H', in substantially the same manner, said apron being held in a relaxed condition and the spring distended 80 by a hinged catch, h', having a bifurcated lip on its upper end in which the cord, h, connecting said apron and spring may be engaged, as is the cord, c, with the catch, c'', on the car.

The magnet, I, on the post is similar to the magnet, E, of the car, and is located directly behind the catch, h, which is of metal. It is connected by an insulated wire, i, with the brush, I', along-side the track at one end, and 90 at its other end is connected with the ground by means of the wire, i'.

The operation of my said invention is as follows: It being desired to deliver a pouch from the car and another to it, the aprons, C 95 and H, are drawn down to the bottom of their respective receptacles as shown in Fig. 1, in which position they are held by the catches, c'' and h', the pouch to be thrown off the car is placed in the receptacle, B, on top of the apron, C, by the postal clerk, and the pouch to be thrown onto the car is placed in the receptacle, G, on top of the apron, H, by the postmaster at the station. As the car passes

said station, the brush, E', comes in contact with the brush, I', which establishes an electrical current from the battery, D, through the wire, e, the magnet, E, the wire, e', the 5 brushes, E' and I', the wire, i, the magnet, I, and the wire, i', to the ground, energizing said magnets, E and I, which operate to draw the metal catches, c' and h', to their poles, back away from the cords, c and h, releasing the 10 springs, C' and H', and permitting them to draw the aprons, C and H, suddenly taut, discharging the pouches therefrom, one into a receptacle or to the ground along-side the track and the other into a suitable receptacle 15 provided on the car.

Having thus fully described my said invention, what I claim as new, and desire to secure by Letters Patent, is—

1. In a mail pouch deliverer, the combination of the delivering mechanism, a catch for holding said delivering mechanism in position to be operated, and an electric magnet located adjacent to said catch and connected with a brush in position to contact with a cir-

cuit-closing connection at that point where 25 it is desired that said catch shall be withdrawn and the delivering apparatus operated, substantially as set forth.

2. The combination, in a mail pouch deliverer, of a receptacle, the flexible apron therein, 30 the cord connecting said apron with an operating spring, a catch adapted to engage with said cord and hold said spring distended, an electric magnet behind said catch, and a brush also connected with said magnet and located 35 to contact with a ground connection and complete an electrical circuit through said magnet at that point where it is desired the pouch shall be delivered, substantially as set forth.

In testimony whereof I affix my signature, in 40 presence of two witnesses, at Washington, District of Columbia, this 1st day of October, 1892.

ERNEST W. BRADFORD.

Witnesses:

EMMA M. GILLETT,
H. KEABLES.
